UNITED STATES PATENT OFFICE.

ALPHONSE A. SEBASTIAN, OF CHICAGO, ILLINOIS, ASSIGNOR TO ANDREW HOFFMAN MFG. CO., OF CHICAGO, ILLINOIS, A CORPORATION OF ILLINOIS.

FOLDING AND SLIDING WINDOW.

1,310,842.

Specification of Letters Patent.

Patented July 22, 1919.

Application filed December 12, 1917. Serial No. 206,718.

To all whom it may concern:

Be it known that I, ALPHONSE A. SEBASTIAN, a citizen of the United States, and a resident of the city of Chicago, in the county of Cook and State of Illinois, have invented certain new and useful Improvements in Folding and Sliding Windows; and I do hereby declare that the following is a full, clear, and exact description of the same, reference being had to the accompanying drawings, and to the numerals of reference marked thereon, which form a part of this specification.

It is an object of my invention to provide a window comprising a plurality of sections which are connected together in such a manner that they may all be simultaneously opened or partly opened, and if opened, will fold together, in which position they may be slid to one end of the frame or into any other position desired.

It is further an object of this invention to provide a window construction in which a plurality of window sashes are pivotally connected so that they all operate together, and which, when opened, or partly opened, may be manipulated as desired to open any portion of the window.

It is furthermore an object of my invention to provide a window construction in which as many window sashes may be connected together as desired, all of which have a slideable connection at the top and bottom and at their sides are interconnected to adjust together, whereby the window may be opened as desired, and regulated and controlled to admit the desired quantity of air or for other purposes, one of which is the cleaning of both sides of the window panes from the inside of a building.

An important object of my invention is the construction of horizontally collapsible sashes which are adapted to be folded together to occupy a small space and which, when folded, may be adjusted or slid into any position in the frame.

Other and further important objects of this invention will be apparent from the disclosures in the specification and drawings.

The invention (in a preferred form) is illustrated in the drawings and hereinafter more fully described.

In the drawings:

Figure 1 is an elevational view of a window embodying my invention.

Fig. 2 is a section taken transversely through the window.

Fig. 3 is a side view of the latch for the window.

Fig. 4 is a front elevation thereof.

Fig. 5 is an enlarged fragmentary vertical section taken through the frame and sash, showing the window open.

Fig. 6 is a section taken on line 6—6 of Fig. 5.

Fig. 7 is an enlarged fragmentary detail section on line 7—7 of Fig. 6.

Fig. 8 is an enlarged fragmentary detail section on line 8—8 of Fig. 6.

Fig. 9 is an enlarged fragmentary detail view of the roller at the upper end of the sash.

Fig. 10 is an enlarged fragmentary view showing the grooved slide plate for the bottom of the sash.

Fig. 11 is a fragmentary detail section similar to that shown in Fig. 8, of a modified form of construction for the bottom of the sash.

Fig. 12 is a fragmentary detail section similar to that shown in Fig. 7, of a modified form of roller construction for the top of the sash.

Fig. 13 is another modified form of construction for the lower supporting portion of the sash.

As shown on the drawings:

The reference numeral 1, indicates the side members of a window frame, 2, indicates the sill, and 3, the top frame member. Rigidly secured by screws or other means to the sill 2, is a guide plate or bar 4, having an upturned rib or flange 5, integral therewith. Secured rigidly in a recess formed in the bottom of the frame member 3, is an inverted channel guide member 6, the margins of the flanges of which are bent inwardly toward one another to form slide rails or supporting guides 7, spaced from each other to form a slot 8, therebetween.

Two window sashes 9 and 10 are shown, but, of course, any number may be used. Said sashes are hinged together along their adjacent inner vertical edges by means of leaf hinges 11, so that both may move together.

Rigidly secured by means of screws 12, on the upper surface of each sash at one end thereof is a plate 13, on which a roller 14, is rotatably mounted by means of a pin 15.

Two window sashes 9 and 10 are shown, but, of course, any number may be used. Said sashes are hinged together along their adjacent inner vertical edges by means of leaf hinges 11, so that both may move together.

Rigidly secured by means of screws 12, on the upper surface of each sash at one end thereof is a plate 13, on which a roller 14, is rotatably mounted by means of a pin 15.

Two window sashes 9 and 10 are shown, but, of course, any number may be used. Said sashes are hinged together along their adjacent inner vertical edges by means of leaf hinges 11, so that both may move together.

The roller 14, fits in the channel member 6, and rests upon the supporting guides 7, while the pin 15, engages in the channel slot 8, as clearly shown in Fig. 7. Secured 5 within a recess or notch by means of screws 16, to the bottom surface and near one vertical edge of each sash, is a plate 17, on which is pivotally secured a block or slide member 18, provided with a slot 19, in 10 which the rib 5, engages.

For the purpose of locking the sash in closed position, a spring lock 20, is attached to one or more of the sashes. The locking bolt of the lock 20, is disposed to engage in 15 an apertured plate or keeper 21, secured upon the sill 2, thus firmly locking the sashes.

Jambs 22 and 23, are secured to the sides of the window frame to permit the stiles 20 of the sashes to fit between said jambs when the sashes are in closed position to provide an anti-rattling and air-tight construction. A window screen 24, is shown mounted in the window frame on the inside of the 25 sashes, and said screen is provided with a hinged section 25, by means of which the lock 20, may be released from the inside of the window to permit adjustment of the sashes.

30 Fig. 11, shows a modified form of construction for adjustably mounting the lower end of a sash, and comprises a plate or track 26, secured upon the sill 2. Said plate has one margin thereof bent upwardly at 35 right angles and then outwardly to form an angle guide portion 27, adapted to engage in a bayonet slot 28, formed in a block or slide member 29, which is pivotally mounted upon a plate 30, secured in a recess or 40 notch formed in the bottom of each sash.

In the modified form of mounting for the upper end of a sash, as shown in Fig. 12, the construction is practically the same as that shown in Fig. 7, with the exception 45 that the roller 14, is replaced by a roller 31, provided with a peripheral groove or recess in which the supporting guides 7, engages, thus holding the roller 31, partly engaged in the channel guide 6, and partly 50 projecting therefrom.

Fig. 13, discloses another modified form of construction for the lower end of a sash, and embraces a plate 32, attached to the bottom of a sash. Said plate 32, has piv-

otally mounted thereon a block or slide member 33, provided with a slot or groove in which a flange or rib 34, of a guide plate 35, engages. Said guide plate 35, is rigidly secured in position on the window frame 60 sill 2.

The operation is as follows:

To open the window, the lock 20, is released and the sashes 9 and 10, are pushed outwardly. Owing to the hinged connection, both sashes move outwardly an equal amount and the rollers 14, track in the guide channel 6, while the slide members 18, slide on the rib 5, of the plate 4. When fully opened, the sashes assume the position 70 shown in dotted lines in Fig. 2. In this position, the sashes may be slid to either side of the window frame against either of the side frame members. It will also be understood that the sashes may be adjusted 75 to any desired position with respect to one another and the frame, to effect any desired opening of the window.

The operation is very simple, and the rollers and guides form a smooth and easily 80 adjustable device, readily permitting the sashes to be folded or collapsed with respect to one another to be slidably moved in any position in the window frame.

I am aware that numerous details of construction may be varied through a wide 85 range without departing from the principles of this invention, and I therefore do not purpose limiting the patent granted otherwise than necessitated by the prior art. 90

I claim as my invention:

In a device of the class described, a window frame, a sash horizontally adjustable within the frame and guided above, a plate disposed at the sill and having an upstanding flange, and a block pivotally mounted at the lower edge of the sash and provided on its lower face with a groove to receive the upstanding flange, the opposite walls of the groove having a bearing engagement on the 100 front and rear faces of the flange.

In testimony whereof I have hereunto subscribed my name in the presence of two subscribing witnesses:

ALPHONSE A. SEBASTIAN.
